United States Patent Office.

JUAN S. L. BABBS, OF NEW ALBANY, INDIANA, ASSIGNOR TO HIMSELF AND
J. B. FORD, OF SAME PLACE.

Letters Patent No. 77,241, dated April 28, 1868.

IMPROVEMENT IN MACHINES FOR MAKING PEGS.

The Schedule referred to in these Letters Patent and making part of the same.

TO ALL WHOM IT MAY CONCERN:

Be it known that I, JUAN S. L. BABBS, of New Albany, in the county of Floyd, and in the State of Indiana, have invented certain new and useful Improvements in Machine for Making Shoe-Pegs; and do hereby declare that the following is a full, clear, and exact description thereof, reference being had to the accompanying drawings, and the letters of reference marked thereon.

In the annexed drawings, making a part of this specification, A represents a suitable base, of any required dimensions, and B represents a large sill or block, to which the framework of this machine is secured, and is secured or fastened to the base, A, in any convenient manner. Said block B is provided with a groove or recess, in which works the bottom of the drive-wheel D, and has the post C secured to it at one end, and the bottom of the frame H secured to the top of its other end, as shown in the drawings.

The post C is provided with a brace, as shown, and supports a suitable shaft, on one end of which is secured the drive-wheel D, and on the other end a pinion or crank, to which power may be applied to give motion to and operate my machine. The top or upper end of the post C, and its brace, are provided with suitable bearings for the above-described shaft.

The frame H has secured to it, crossways, another frame, I, the sides of which are grooved, and form suitable ways for the movable table M to slide on. Said frame H has secured to its top, or forming a part of it, longitudinal-grooved ways G, upon which slides and works the movable cutter-head F.

Supported and adjusted in and a little below the grooved ways of the frame I is a screw-shaft, w, and a collar or sleeve-shaft, J. Upon one end of the screw-shaft w is secured a small ratchet or cog-wheel, L, which is operated, and said shaft thereby turned either way that may be desired, by means of the pawls v v. The sleeve-shaft J embraces and works on one end of the screw-shaft w, close to the ratchet L, and is supported at the other end in the cross-bar of the frame I. Said shaft is provided with projections or forks t t, which press against a small spring, u, when desired, by partially revolving the shaft J.

The shaft J is operated or partially rotated by means of the spiral-spring chains Q Q, which are secured to each of the levers O O, as shown in the drawings, and which are operated by said levers.

O O represent levers, pivoted at their lower ends to the base, A, and operating or moving in a groove in the end-piece of the frame I, as shown in Figure 1, one on each side of the shaft J. These levers are chained together or secured near their upper ends by means of a strap or chain, z, and have the spiral-spring chains Q Q secured one to each, by which the shaft J is operated, as desired. Said levers are also connected with or attached to another lever, m, by means of chains j j, by which means said horizontal lever m is operated.

N N represent levers, pivoted to the side of the beam or block B in a vertical position, and each has a plate or strip, P, pivoted to it, said plates being pivoted together and to another plate, R, as shown in the drawings.

The plate or lever R embraces the end of the screw-shaft w, and between the end of the shaft J and the ratchet-wheel L, and has the double-catch pawl v v secured to its upper end, which works in and operates the said ratchet-wheel and its shaft w. This lever R is operated with the double pawl v v by means of the levers N N and the strips P P.

Attached to one of the levers N is a spiral spring, T, one end of which is fastened to the block B. This spring T is designed to bring the two levers N N back to a vertical position when either one of them is forced or drawn out of said position. The levers N N are moved or operated by means of the sliding-cutter table or head F, which is operated directly by means of the drive-wheel D and its connecting-rod E.

Gauges h h, made adjustable, are fastened to one side of the grooved ways, so as to regulate the length of stroke of the levers N N, and thereby the speed of the screw-shaft w.

A small spring, u, embraces the shaft J, and is fastened to the pin which pivots the double pawl v v to the end of the lever R. Said spring serves to throw the pawl v v into gear either way by means of the projections t t, when the shaft J is turned by one or the other of the levers N N.

S represents a lever, pivoted to the side of the block D, under the ratchet-wheel L, the upper end of which is bifurcated, forming suitable catches or pawls, v' v'. Said pawls serve to hold the ratchet-wheel L from turning backward when the machine is in operation. This lever is operated by means of the lever m, which is in turn operated either way by the chains j j and levers O O. The lever m is pivoted at one end to a suitable post, n, and extends thence horizontally to the bottom of the lever S, to which it is attached.

By placing one of the levers O into one of the notches, x, at the end of the slot in the frame I; the shaft J is turned by means of the spring-chain Q, so that one of the projections t presses against the spring u, which throws one side of the double pawl v v into gear with the ratchet-wheel L, and at the same time the lever m, by means of the chain j, presses the lever S so that one of its pawls v' catches in the ratchet-wheel L. Then, by turning the crank, and giving motion to the sliding-cutter-table or head F, which operates the levers N N, motion is given to the screw-shaft w; and to reverse the motion of said shaft, it is only necessary to withdraw the lever O from the notch x, and put the other lever O in the opposite notch x.

The movable feed-table M is made so as to exactly fit and work on the grooved ways I, and has a bar, d, secured to one side thereof, which passes through a suitable hole, and detaches the lever O from the notch x when said table is moved or approaches one end of the frame I. This table M is operated, or moved backward and forward on the ways of frame I, by means of a nut or female screw working on the screw-shaft w, and having one end thereof secured to the aforesaid table.

On top of the table M is pivoted a circular disk, also marked M in the drawings, which is intended to secure the block of wood for the pegs by means of a series of set-screws, ll, around the periphery thereof. This disk M is arranged so as to turn one-fourth around on its axis, so as to turn the peg-block that it may be pointed and split both ways without readjustment on the table. The disk is held steady in its place, where desired, by means of a spring-catch, r. It is intended to use a rubber or elastic band around the peg-block, so as to hold the parts thereof firmly together when it has been pointed and split one way, that it may be pointed and split the other way. A small lever, a, is pivoted across the end of the frame I, and is attached at one end to a sliding bar, b. This lever a and sliding bar b are operated by means of a small pin or projection, c, on the sliding table M.

When the table M approaches the end of the frame I to which is pivoted the lever a, the pin c operates or presses said lever and the sliding bar so that the opposite end of said bar b detaches the lever O from the notch x, when the table M remains stationary, and the disk and peg-block thereon may be turned, after which the other lever O may be placed in the other notch x, and the table M will work or move back toward the other end of the frame I.

F represents a sliding or movable table or cutter-head, which is made so as to fit and work in and on the grooved ways G, and has adjustable gauge-catches g g secured to one side thereof. These gauge-plates g g are for the purpose of assisting in regulating the length of stroke or vibration of the levers N N. In the middle of the table F is a suitable slot or hole, in which works an adjustable head, K. The adjustable head K is operated up and down, so as to correspond with the length of peg to be made, by means of a screw, which, for convenience, is provided with a crank, f.

Two knives or cutting-bits, p p, of shape suitable for cutting the notch or groove for pointing pegs, are secured to the head K, arranged with their cutting or ploughing-edge in opposite directions, as shown in the drawings, so as to cut both ways.

Between the two bits p p is fastened a knife, q, which is made with a curved edge, as shown, and considerably thicker in the middle than elsewhere, tapering or bevelled both ways towards its opposite ends, so as to split the peg-blocks as fast as the same are pointed, and for which purpose this knife q is designed.

Having thus fully described my invention, what I claim as new, and desire to secure by Letters Patent, is—

1. The splitting-knife q, and cutting-bits p p on the under side of the movable head K in the sliding frame F, when arranged to operate substantially as specified.
2. The arrangement of the table M upon the ways I, screw-shaft w, ratchet-wheel L, double pawls v v, levers R and N N, connecting-strips P P, and spring T, in combination with the movable frame F, the several parts being constructed to operate substantially as set forth.

In testimony that I claim the foregoing, I have hereunto set my hand, this day of , 1867.

JUAN S. L. BABBS.
